Atty.

UNITED STATES PATENT OFFICE.

ANTHONY L. J. SEEHAAS, OF PEORIA, ILLINOIS.

MACHINE FOR CUTTING AND PRINTING AT ONE OPERATION.

1,372,201.

Specification of Letters Patent. Patented Mar. 22, 1921.

Application filed November 10, 1919. Serial No. 336,877.

To all whom it may concern:

Be it known that I, ANTHONY L. J. SEEHAAS, a citizen of the United States, residing at Peoria, in the county of Peoria and 5 State of Illinois, have invented certain new and useful Improvements in Machines for Cutting and Printing at One Operation; and I do hereby declare that the following is a full, clear, and exact description of the 10 invention, which will enable others skilled in the art to which it appertains to make and use the same.

This invention relates to a machine for cutting and printing paper. It relates particularly to a machine into which paper may 15 be fed in sheets, said machine being adapted to cut the paper to a desired size or width and also to print upon it at one operation.

A machine of this type is desirable for 20 several purposes, one of which is that of cutting sheets of paper currency into note size and placing on each note, by means of type, the names of certain officers of the bank issuing the currency, all at one operation.

An object of the invention is to provide 25 a machine that will both separate a sheet of paper into strips and print upon each strip by means of type in one operation.

Another object is the provision of a 30 machine having a series of rolling cutters, and a series of printing devices that will print upon the paper in a certain desired position thereon during its passage through the said cutters.

Still another object is the provision of a 35 machine having paper feeding and severing mechanism and printing mechanism, so timed during operation that while cutting 40 the paper the printing, automatically done, will be placed in a required position thereon.

Still another object is that of providing a 45 hand-operated machine for simultaneously cutting and printing paper so arranged and operated that the printing act can be made to occur but once upon paper of varying lengths, and in the same position thereon.

That my invention may be understood I 50 have provided the accompanying drawings showing several methods of constructing a machine under my invention, it being understood that changes may be made as will best attain the objects sought.

Figure 1 is a longitudinal sectional elevation 55 of a machine involving my invention in one of its forms.

Fig. 2 is a plan of the same.

Fig. 3 is a sectional elevation of a machine of a slightly modified form.

Fig. 4 is a plan of a portion of the same 60 form of machine.

Fig. 5 is a sectional elevation of a portion 65 of a further modification, and

Fig. 6 is a plan of a portion thereof.

One of the specific uses to which my invention is adaptable is that of severing and printing paper currency which is furnished usually in sheets of four bills each to banking institutions. These sheets are to be cut, and each bill must receive the names of certain officers of the bank from which it is 70 issued.

It has been the custom to separately cut and stamp or print these bills which is unsatisfactory and involves much labor besides 75 the loss of considerable time. It is the purpose of my invention, therefore, to provide for both these necessities at one operation, and while I am aware that there are machines for cutting these sheets into separate 80 portions and printing them at one operation, that described herein I believe to be of novel construction, simple, and quite effective.

In Figs. 1 and 2, the numeral 1 indicates 85 two side frame portions of the machine and 2 a table mounted upon them for receiving the work to be handled, said portions 1 being suitably braced by means not necessary to show herein.

3 is a shaft journaled at its ends in the said portions 1 and provided with a series of circular cutters 4 rotatable therewith, the peripheries of said cutters being substantially in line with the upper surface of the 95 table 2. Beneath the shaft 3 is a shaft 5 also journaled in the said portions 1 and having a series of cutters 6 companion to and adapted to bear laterally against the cutters 4 whereby the sets of cutter's will 100 produce a clean cutting action. Preferably the said cutters 6 are spring-held against the said companion cutters by any suitable means not necessary to describe herein, since no claim to novelty is made thereto.

The shafts 3 and 5 are provided each with a gear 7 and 8 respectively, meshing with one another, the relation thereof being such that the cutters 4 may be rotated a trifle faster than the cutters 6 by extending the 110 pitch circle of the gear 8 slightly inside the peripheries of the said cutters 4 to produce

a cleaner shearing action, though this may not be necessary.

9 and 10 indicate a pair of feed rolls journaled between the portions 1, adapted to work in conjunction, their places of meeting being in line with the upper surface of the table 1 as shown.

- 10 The roller 10 is furnished with a gear 11 to mesh with an idler-gear 12 on the side of the machine in mesh with and driven by the gear 8. The roller 9 is free to rise and fall within a recess 13 and rotates, due to its considerable weight, by frictional engagement with the roller 10. The shaft 5 is 15 furnished with a cam 14, and 15 is a lever pivoted on the machine at 16, one end being in position to be engaged by the cam 14, its other end lying just beneath one of the trunnions of said roller 9.
- 16 20 17 is a shaft extending between and journaled in the portions 1 and, in the present instance, has secured thereon at desired intervals rollers 18 provided with printing type 19.
- 25 20 indicates a series of inking rolls to rotate in contact with said rollers 18, being mounted on a shaft 21 for example.

One end of the shaft 17 has a gear 22 in mesh with an idler-gear 23 which, in turn, 30 meshes with the gear 7 of the shaft 3. 24 is a table, the position of whose upper surface is such as to receive the pressure of the printing type in the rotation of the rollers 18.

35 The shaft 5 is operated by a crank 5' for example and when turned to the right rotates the feed roll 10 in the same direction through the idler-gear 12 so that paper lying between the feed rolls when held by 40 the same will be carried toward and between the cutters 4 and 6.

In cutting a sheet into strips the cutters 4 and 6 are preferably employed to act as stops against which the edge of the sheet is 45 placed before the cutting begins, and in order that this may be done the upper feed roll 9 is raised automatically to permit entrance of the paper. That is to say, the cam 14 in each revolution of said cam 14 50 lifts the roll 9 by means of the lever 15 so that the sheet may be inserted and moved up against said cutters, whereupon the said roll is permitted to descend upon the paper as the cam passes from beneath the lever, 55 both rolls holding the paper firmly, feeding it through the cutters in positive manner.

If we suppose the printing rollers to have a certain peripheral speed, the feed roller 10 should have a speed of peripheral travel 60 at least as fast in order that the paper will feed in proper manner thereto.

The speed of rotation of the cutters must be at least as fast as the speed of the feed roll 10 and the printing rollers. The said 65 printing rollers may print the full length

of the sheet or merely a part thereof, depending upon whether the type extends entirely or but part way around them and in order that the printing shall not take place more than once upon the bill, the printing roller may be of such a circumference that the bill will pass entirely through before the type will come around for a second impression, the peripheral travel of the type surface in any event being equal, of course, to the speed of travel of the medium printed upon, as explained.

In the operation of the type of device shown in Fig. 1, the printing rollers are suspended at such a distance from the table 24 80 that no part thereof will have contact with the latter. It is only when the edge of the paper has reached a point beneath the roller, where the type in the rotation of the roller is to meet it, that pressure of the said roller 85 takes place.

The rotating parts may have such a relation to one another that when the type 19 of the printing rollers is in the position shown in Fig. 1, the paper will be just entering beneath the rollers in position to be printed as said rollers rotate, the roller 9 having been previously raised to admit the paper to be passed to and through the cutters. In passing through the machine, the 95 paper even after having left the feed-rollers will still be drawn forward by the cutters in their action and fed toward and beneath the printing rollers and the latter will in turn draw the paper through after having left 100 the cutters.

As arranged in said Fig. 1, the crank 5' Fig. 2, is turned until the lever 15 has lifted the roller 9, the paper being then passed between the rollers 9 and 10 against 105 the cutters. By a continued action of the crank, the lever now permits the roller 9 to descend for clamping the paper which is then positively fed into the cutters until having reached the printing rollers, as explained, the type thereof is brought into position for printing.

The cutters and printing rollers having the same peripheral speed, the bills having been cut in one rotation, for example, of 115 the former, the latter will print the signatures in the travel of the bills and take up a position where the type will be ready for a succeeding like operation, the roller 9 again lifting for the insertion of the paper. 120

The starting position for operation may be determined in any suitable way as by bringing one of the movable parts to a given position.

Another form of mechanism is shown in 125 Figs. 3 and 4 whereby the cutting and printing is also accomplished in one operation, the same reference characters being used to designate corresponding parts. In this form, where it may be found of advantage 130

to provide for vertical movement of the printing rollers 18, the shaft 17 carrying such rollers may be carried in a boxing 17' at each end, but one of which is shown, slid-
5 able in a recess 17' in the portions 1.

The shaft 3 has a cam 3', and a lever 3' pivoted between its ends on the machine, opposite ends thereof being in position to engage the said cam and the said shaft 17,
10 which structure may be duplicated at the other end of the machine by extending the shaft 25 carrying the lever 3' the full width of the machine and transferring rocking motion to said other end similarly furnished
15 with a lever, not shown. The cam may be so constructed that the said shaft 17 will be held up for as long or short periods as desired. By this structure the rollers may be held clear of the paper and let down only
20 at the time desired for printing.

In Figs. 5 and 6 is illustrated still another form wherein the aim is that of printing upon a sheet but once even when said sheet is of considerable length and when the
25 printing roller is much shorter in circumference than the length of said sheet.

The reference characters again agree with those already given. As before, the shaft 17 with its printing rollers is vertically movable, there being a lever 4' pivoted between its end on some part of the machine, one end engaging beneath the shaft 17, its other end being in position to engage a cam 5' on
30 shaft 5, the inking roll 20 in either of the forms last described by reason of the soft nature thereof permitting the vertical movement by receiving the type into them.

The cam will cause the printing rollers to be lifted and sustained until at a proper
40 moment when a certain zone of the sheet has been brought adjacent the rollers, whereupon the shaft 17 is permitted to drop to printing position.

In any of the forms herein shown the peripheral speed of the feed-roller 10, the cutter 6, and the type surfaces of the printing rollers 18 must, of course, be the same and at their surfaces must be substantially the same as the pitch circles of the several
45 gears 11, 8, and 22 respectively that this may be the result.

Furthermore, the cams 14, 3', and 5' must be only of such extent and be so placed that the movement of parts controlled by them
55 will occur at the proper times for the operations described, it being required, for instance, that after the feed roller 9 has been lifted and the paper has been placed against the cutters that the said roller will immediately descend to start feeding the paper, the type 19 during the interval between travel of the paper from the cutter to the printing rollers moving to the position for printing as the paper passes beneath the latter. So
60 far as the vertical play of the shaft 17 is

concerned it is but slight, of course, and there is therefore no danger of the teeth of the gear 22 and idler 23 becoming unmeshed.

My machine is adaptable for many uses in cutting and printing, being of particular value in its more simple form for the treatment of paper money as already explained.

I claim:

1. In a machine of the class described, in combination with a pair of rotating cutters, a pair of rollers for feeding material thereto one of them being separable from the other, and a printing roller, all of the parts being 75 geared together, of a lever adapted to engage the separable roller, and a cam adapted to engage the lever, the engagement of said cam being timed to act to move and release the last named roller in a certain position of the said printing roller. 85

2. In a machine of the class described, in combination with a feed roller, a cutter and a printing roller connected to rotate together, and a second feed roller co-operating with the first described one adapted for separation 90 therefrom, of a lever engaging the said second roller, a cam operated from one of the described parts to engage the lever, the action of the lever through the cam being timed to the rotation of the said printing 95 roller whereby to raise and release the said second feed-roller at a predetermined time with respect to the printing act.

3. In a machine for cutting and printing paper, in combination with a pair of feed-rollers one of them being mounted whereby it may be separated from the other, a printing roller and a pair of rotating cutters stationed between the said feed rollers and the said printing roller, the stationary roller, 100 one of the cutters, and printing roller being arranged to rotate at the same peripheral speeds, said cutters constituting a stop for the paper, of a lever mounted upon the machine engaging at one end the separable 110 roller, and a cam operated from one of the described parts adapted to engage the opposite end of the lever to separate the movable roller from the other to permit placing the paper against the cutters, said cam 115 adapted in its rotation to release the lever and through it the said movable roller to cause feeding of the paper through the cutters, the release of the roller being timed whereby in the rotation of the printing 120 roller the paper upon reaching the same will be printed upon at a definite point during its travel.

4. In a machine for separating and printing sheets of bank notes, in combination, a 125 frame, a pair of engaging feed-rollers journaled thereon, one of them being separable from the other, a printing roller journaled on the frame, a pair of cutters revolvably mounted also on the frame be- 130

5. tween the said feed-roller and the printing-
5 roller, one of the feed-rollers, one of the
cutters and the printing roller having identi-
10 cal peripheral speeds, a cam rotatable with
one of the described members, and means
operated thereby in its travel to move the
separable feed roller for admitting the
medium to be operated upon between said
15 feed rollers for placing it against the said
cutters, and then to release the said movable
roller whereby to feed the medium through
the cutters to and beneath said printing
roller, said cam in its travel releasing the
20 feed-roller at a predetermined time in the
rotation of said printing roller.

25 5. In a machine for separating and print-
ing sheets of bank notes, the combination
of a frame, a pair of cutters, a printing
20 roller and a pair of feed engaging rollers
revolvably mounted thereon arranged to ro-
tate at the same peripheral speed, one of
said feed rollers being movable in its bearing
whereby to be separable from the other
25 roller, a lever mounted on the frame, one
end thereof adapted to engage the separable
roller, and a cam rotatable with one of the
described rotating members adapted to en-
gage the other end of the lever whereby
30 to move the separable roller at a predeter-
mined time during the rotation of the
printing roller.

6. The combination in a machine for
cutting a paper sheet into sections including
rotating cutters, feed rolls and mechanism
to drive the same, of a series of printing 35
rollers operated by said mechanism, each
adapted to place an impression on one of the
sections of said sheet, a mounting for the
rollers adapted for movement substantially
perpendicular to the plane of the paper, 40
and mechanism adapted to lift the rollers
from their impressing position at pre-
determined intervals.

7. In combination with a series of cutters
for dividing a paper sheet into a series of 45
separate portions and mechanism for oper-
ating said cutters, of a series of printing rolls-
ers each adapted to place an impression upon
each section operated by said mechanism,
all of said rollers adapted to have movement 50
substantially perpendicular to the paper
surface, a lever to engage and lift the said
rollers, and a cam portion on a part of the
mechanism for engaging the levers at pre-
determined intervals to cause the rollers to 55
be lifted.

In testimony whereof I affix my signature
in presence of two witnesses.

ANTHONY L. J. SEEHAAS.
